UNITED STATES PATENT OFFICE.

FRANK SHUMAN, OF PHILADELPHIA, PENNSYLVANIA.

UTILIZING HEAT FOR THE DEVELOPMENT OF POWER.

1,002,768.

Specification of Letters Patent. Patented Sept. 5, 1911.

Application filed July 20, 1907. Serial No. 384,722.

To all whom it may concern:

Be it known that I, FRANK SHUMAN, a citizen of the United States, residing in Philadelphia, Pennsylvania, have invented 5 certain Improvements in Utilizing Heat for the Development of Power, of which the following is a specification.

My invention consists of an improvement in that method of generating power which 10 consists in vaporizing a power-developing agent, having a relatively low boiling point, by means of the waste heat of compression, or of furnaces, or by a heating agent of relatively low temperature, such as the rays 15 of the sun, the object of my invention being to effect the carrying out of such process in a more practicable and economical manner than any theretofore devised and with which I am familiar.

20 The accompanying drawing shows, in a diagrammatic way, apparatus for carrying out my invention.

The essential feature of my invention consists in employing, as a power-developing 25 agent, a compound consisting of an element having a relatively high boiling point combined or charged with an element having a lower boiling point. This compound will hereinafter be referred to as "strong liquor" 30 and may consist of any elements having the properties named and capable of being combined for use in the manner described. As instances of such compound I may mention a compound of ammonia gas and water 35 or of ether and lubricating oil. The strong liquor thus constituted is subjected to the action of the heating agent, whereby a high percentage of the element having a low boiling point will be vaporized or otherwise 40 freed, under pressure, from the compound, the remaining portion of the latter, consisting of the element having a high boiling point and the remaining small percentage of the element having a low boiling point 45 being termed "weak liquor". Vapor or gas under pressure thus produced is employed in any suitable engine for the development of power, and on being exhausted therefrom is mixed with the weak liquor, which has 50 meantime been reduced in temperature to such an extent that it will not only condense the exhaust vapor but will absorb the same and thus be restored to its original condition of strong liquor, which can be returned to 55 the generator for revaporization, being, by preference, on the way, subjected to the ac-

tion of the weak liquor flowing from the condenser to the cooler so as to absorb heat therefrom preparatory to entering the generator.

In the drawing, 1 represents the generator or means for imparting heat to the strong liquor, the generator which I have selected for purpose of illustration being a solar heat absorber and having, at the top, 60 a valved pipe 2 which serves to convey the vapor or gas under pressure from the generator to an engine 3 of any suitable character in which such pressure is utilized, the exhaust from the engine being effected 65 through a valved pipe 4, which is coiled within a vessel 5 having a valved inlet pipe 6 and overflow pipe 7, so as to provide for the passage through said vessel of water or other cooling agent, the coil terminating in 70 a valved pipe 9 which feeds a pump 10 driven by the engine 3, or in any other suitable manner, the valved discharge pipe 11 of said pump communicating with the upper 75 end of the generator 1. That portion of the pipe 11 between the pump and the generator is inclosed in a casing 12 and the upper end of the latter is in communication through a valved pipe 13 with the lower end of the generator, the lower end of the casing 80 communicating through a valved pipe 14 with a coil 15 contained in a vessel 16, having valved inlet and outlet pipes 17 and 19, so as to provide for a flow of cooling fluid 85 through the same, the coil 15 terminating 90 in a valved pipe 20 which discharges into the exhaust pipe 4 of the engine.

That element of the strong liquor having the low boiling point, on being subjected to heat in the generator 1, is vaporized or 95 otherwise separated from the element having the higher boiling point, vapor or gas under pressure thereby produced then passing to the engine 3, and any exhaust from the latter being brought into contact with the 100 weak liquor derived from the lower portion of the generator, this hot weak liquor being first cooled by contact with the feed pipe 11, whereby the strong liquor is fed into the upper portion of the generator, the weak 105 liquor being in contact with this pipe during its flow through the heat exchanger 12 and being thereby not only partially cooled but also serving to increase the temperature of the cold strong liquor before the latter enters 110 the upper portion of the generator. After leaving the heat exchanger the weak liquor

is further cooled in traversing the coil 15 and in its weak and cold state is mixed with the vapor exhausted from the engine, the mixture being subjected to the cooling influence of the agent in the vessel 5, before flowing to the pump 10. Reduction of the temperature of the weak liquor causes it to absorb the vapor or gas exhausted from the engine, so that it is now in condition to return, as strong liquor, to the generator for revaporation.

By reason of my invention I am enabled to generate vapor or gas under high pressure with less danger than if an agent having a low boiling point, such as ammonia or sulfurous acid, was used alone, the greater safety being due to the fact that the very energetic action of the element having the low boiling point has been tempered by the use of a diluent, and the employment of the latter also enables me to use generators having heat absorbing surfaces of large area, which could not be used if the element having a low boiling point was employed alone because of the expense involved in the employment of large volumes of such element. One of the particular advantages of my invention, however, arises from the fact that by the introduction of the cold weak liquor into the exhaust pipe of the engine, this cold weak liquor coöperates with the cooling agent in the vessel 5 to effect condensation of the exhaust vapor, and said condensation is thereby greatly facilitated, with the ac-

companying advantage of reduction of back pressure in the engine, whereas, if the condenser alone was relied upon, the vapor or gas of the engine exhaust would not be condensed to liquid form by the use of condensing water at ordinary temperature except under a high back pressure.

I claim:—

The mode herein described of utilizing heat for the production of power, said mode consisting in subjecting to the heat a compound containing two elements, one of which has a higher boiling point than the other, thereby vaporizing or otherwise freeing from the compound, under pressure, the element having the lower boiling point, utilizing the vapor under pressure as a motive power fluid, absorbing the exhaust vapor by means of a cooler supply of the element having the higher boiling point, returning the resulting liquid to the heater, and subjecting it, during such return, to the action of a heated body of the element having the higher boiling point while the latter is on its way from the vaporizer to a cooler for subsequent admixture with a fresh supply of the exhaust vapor.

In testimony whereof, I have signed my name to this specification, in the presence of two subscribing witnesses.

FRANK SHUMAN.
